(57) **CLAIM**

The ornamental design for an imaging apparatus with display screen as shown and described.

DESCRIPTION

FIG. 1 is a front view of an imaging apparatus with display screen according to the claimed design.

FIG. 2 is a front-right perspective view of the imaging apparatus with display screen.

FIG. 3 is a front-left perspective view of the imaging apparatus with display screen.

FIG. 4 is a left side view of the imaging apparatus with display screen.

FIG. 5 is a top-front-left perspective view of the imaging apparatus with display screen in a use environment.

FIG. 6 is a front view of the imaging apparatus with display screen in the use environment of FIG. 5.

FIG. 7 is a rear view of the imaging apparatus with display screen in the use environment of FIG. 5.

FIG. 8 is a left side view of the imaging apparatus with display screen in the use environment of FIG. 5.

FIG. 9 is a right side view of the imaging apparatus with display screen in the use environment of FIG. 5.

FIG. 10 is a top view of the imaging apparatus with display screen in the use environment of FIG. 5.

FIG. 11 is a bottom view of the imaging apparatus with display screen in the use environment of FIG. 5.

FIG. 12 is a front view of the imaging apparatus with display screen in another use environment.

FIG. 13 is a rear view of the imaging apparatus with display screen in the use environment of FIG. 12.

FIG. 14 is a left side view of the imaging apparatus with display screen in the use environment of FIG. 12.

FIG. 15 is a right side view of the imaging apparatus with display screen in the use environment of FIG. 12.

(Continued)

FIG. 16 is a rear-left perspective view of the imaging apparatus with display screen in the use environment of FIG. 12.

FIG. 17 is a top view of the imaging apparatus with display screen in the use environment of FIG. 12; and, FIG. 18 is an enlarged partial front view of area 18 in FIG. 1.

The broken lines in the drawings illustrate portions of the imaging apparatus with display screen that form no part of the claimed design.

The dash-dot-dot broken lines in FIGS. 1 and 18 illustrate boundaries of the enlarged view that form no part of the claimed design.
